UNITED STATES PATENT OFFICE.

JESSIE C. POPE, OF LONGVIEW, TEXAS.

RAILWAY TIE, RAIL FASTENER, AND RAIL JOINT.

Application filed December 7, 1926. Serial No. 153,049.

The purpose of this invention is the provision of a new and improved railroad or railway tie and rail joint of the metallic hollow body type, having for its primary object a tie of simple and durable construction.

A further object of the invention is that the tie provides in its construction a means for solidly supporting the railway rails, the weight placed upon the rails receiving support through the tie and not merely upon the shell of the tie, as is the practice of some types of these ties heretofore patented.

The invention also includes as one of its features a railway tie which forms a support for both sides of each rail, and prevents the need of spikes, ordinarily used to fasten the rails to the ties.

With the above objects in view, the invention will be clearly understood from a perusal of the following description in connection with the accompanying drawings and wherein:

Figure 1 represents a side elevational view of a metallic railway tie embodying the invention, the tie being partly broken away and illustrating in section the rail supporting elements.

Figure 2 represents an end elevational view of the tie with a portion of a rail supported thereupon.

Figure 3 is a cross-sectional view, along the line 3—3 of Figure 1.

Figure 4 is a perspective view of one of the rail supporting plates, including a portion of its co-acting rod; and

Figure 5 is a perspective view of a modified form of the plate shown in Figure 4, for connecting the ends of two adjoining rails.

Figure 6 is a detail fragmental view in side elevation of the rail connecting plate, and the ends of two rails, illustrating the operable use of the plate in Figure 5.

Proceeding in accordance with the drawings and wherein similar numerals designate the various parts of the invention, 1 denotes a metallic railway tie of hollow type made of cast metal or the like. This tie is of one continuous formation, the top being open along the center from end to end longitudinally of the tie as indicated at 2 and is open at both ends as will be apparent from Figure 2.

In some types of metallic railway ties the rail rests upon the shell body, but in the present invention there is provided a clamp

block 3. This block is clearly shown in Figure 4 and includes a central upward protuberance 4. The block is of such shape and dimensions as to enable it to be snugly received inside the tie so that the protuberance projects beyond the tie. In laying a railway track a block is placed, one opposite the other, in pairs at suitable distances apart along the rails. The rail 5 is seated in the groove 6 in such manner, and as clearly shown in Figure 1, that the foot of the rail is supported in the bottom of the grooves 6 while the web 7 of the rail lies snugly against the underside of the curved-over portion 8 of the protuberance 4. In addition to this the shoulders 9 of the block abut the underside of the top of the tie. In this manner the rails are provided with a solid support through the tie, the rails resting also partly upon the ties.

To maintain the blocks in upright position, each one of the pair is fastened by bolts 10 to the tie and all of the blocks are connected by a rod 11. Nuts 12 are then advanced upon the rod to tighten the blocks to the rails. The inside block which is not bolted to the tie is held tightly against the rail by a washer 13 which bears against the block, and the outside block which is not bolted to the tie is brought up snugly against the rail when the nuts are advanced and tightened in position.

In Figure 5 is shown a modification of the clamping block to be used at the joining of the rail ends. In this modification the protuberance 4 has formed thereon a T head 14 including bolt holes 15 for fastening to the rail ends. The T head when in place lies next the web of the rail in the same manner as the ordinary protuberances on the regular clamping blocks. The rails at the joints are thus firmly connected, the rails at this point being firmly supported.

Obviously the invention may include further modifications and alterations consistent with the principle involved and including equivalents known in the art and in keeping with the appended claim.

What is claimed is:

A railroad tie of the class described including a hollow member angular in cross section and open at its ends and top, an inturned longitudinal flange at each side of the top of the member, said flanges constituting rail supports, a block fitted snugly within said member adjacent one end, a recessed neck integral

with the block and projecting between the flanges for engaging the outer base flange of one rail of a track, a similar block in the member adjacent its other end, a recessed neck extending therefrom between the flanges for engaging the inner base flange of the other rail of a track, means extending transversely through the blocks and the hollow member for holding them together fixedly, blocks fitted snugly within the hollow member and adjustable longitudinally thereof, one of said blocks having a recessed neck projecting between the flanges for engaging the inner base flange of the first named rail, the other block having a recessed neck for engaging the outer

base flange of the second named rail, a rod extending longitudinally of the member through all of the blocks, a collar on the rod, means threaded on one end portion of the rod for shifting said rod longitudinally, thereby to bind the collar against one of the adjustable blocks to shift it toward the adjacent fixed block, thereby to clamp the rail positioned between said blocks, and means threaded on the other end of the rod for engaging the other adjustable block to shift it relative to the adjacent fixed block, thereby to clamp upon the rail between the necks of said blocks. 20 25

In testimony whereof I affix my signature.
JESSIE C. POPE.
